[57] CLAIM

The ornamental design for a worklight comprising twin halogen floodlights and an adjustable stand, as shown and described.

DESCRIPTION

FIG. 1 is an isometric view of a worklight comprising twin halogen floodlights and an adjustable stand, the worklight embodying the design of the present invention.

FIG. 2 is an enlarged front elevational view of one of the two floodlights with a fragmentary portion of the light bar with the cord broken away for convenience of illustration only; FIG. 3 is an enlarged top plan view of one of the two floodlights with a fragmentary portion of the light bar; FIG. 4 is an enlarged rear elevational view of one of the two floodlights with a fragmentary portion of the stand and the light bar; and,

FIG. 5 is an enlarged side elevational view of one of the two floodlights and the light bar with fragmentary portions of the stand.
